(57) **CLAIM**

The ornamental designs for a wire guard, as shown and described.

DESCRIPTION

FIG. 1 is a front perspective view of a first embodiment of the wire guard;

FIG. 2 is front plan view;

FIG. 3 is a rear plan view thereof;

FIG. 4 is a right side view;

FIG. 5 is a left side view;

FIG. 6 is a bottom view;

FIG. 7 is a top view;

FIG. 8 is a front perspective view of a second embodiment of the wire guard;

FIG. 9 is front plan view of the wire guard of FIG. 8;

FIG. 10 is a rear plan view of the wire guard of FIG. 8;

FIG. 11 is a right side view of the wire guard of FIG. 8;

FIG. 12 is a left side view of the wire guard of FIG. 8;

FIG. 13 is a bottom view of the wire guard of FIG. 8; and,

FIG. 14 is a top view of the wire guard of FIG. 8.

The broken lines in the drawings illustrate portions of the wire guard and form no part of the claimed design.

1 Claim, 11 Drawing Sheets
